UNITED STATES PATENT OFFICE.

EDWIN R. THOMAS, HENRY POKORNEY, AND CARL THORDEN, OF BUFFALO, NEW YORK; SAID POKORNEY AND THORDEN ASSIGNORS TO SAID THOMAS.

DESIGN FOR A MOTOR-SUPPORTING MEMBER FOR MOTOR-CYCLE FRAMES.

SPECIFICATION forming part of Design No. 33,974, dated January 22, 1901.

Application filed December 24, 1900. Serial No. 40,978. Term of patent 7 years.

To all whom it may concern:

Be it known that we, EDWIN R. THOMAS and HENRY POKORNEY, citizens of the United States, and CARL THORDEN, a subject of the King of Sweden and Norway, residing at Buffalo, in the county of Erie and State of New York, have invented and produced a new and original Design for a Motor-Supporting Member for Motor-Cycle Frames, of which the following is a specification, reference being had to the accompanying drawing, forming a part thereof.

This design relates to the configuration of a motor-supporting member for a motor-cycle frame.

The accompanying drawing is a perspective view of a motor-cycle frame member embodying our design.

As shown in the drawing, the leading feature of our design consists of two straight bar-sections A A', which are connected by a loop B, two front hangers C C, depending from the front part of the loop, and a rear hanger D, depending from the rear bar-section A'. The ends b of the loop are rounded, one side b' thereof is straight, and the other side thereof is provided with an outward bend or offset b². The front hangers are arranged side by side and each consists of an arm c', which 30 curves downwardly and rearwardly from the

front end of the loop and is provided at its lower end with a segmental ear or plate c². The rear hanger D consists of a front arm d, which extends downwardly from the rear bar-section A' adjacent to its junction with the loop B, a rear arm d', which inclines forwardly from the rear end of the rear bar-section, and a pair of segmental ears or plates d², connecting the front and rear arms d d' of the rear hanger. The bar-sections A A', the loop B, and the arms c' d d' of the hangers are provided with longitudinal ribs e. The segmental ears or plates of the front and rear hangers are arranged concentrically, and each of these ears or plates is provided in its central part with a longitudinal slot f and at its ends with perforations g.

What we claim is—

The design for a motor-supporting member for a motor-cycle frame, substantially as hereinafter shown and described.

Witness our hands this 8th day of September, 1900.

EDWIN R. THOMAS.
HENRY POKORNEY.
CARL THORDEN.
